METHOD FOR TREATING OIL

Rudolph C. Osterstrom, Kenilworth, Ill., assignor
to The Pure Oil Company, Chicago, Ill., a cor-
poration of Ohio

Application October 5, 1934, Serial No. 747,015

11 Claims. (Cl. 196—50)

This invention relates to the manufacture of gasoline motor fuel of a desired anti-knock value or boiling range, or both, and of desired purity and stability with respect to color- and gum-forming constituents, from gasoline or naphtha, produced either by simple distillation or by pyrolysis from petroleum or petroleum oils, and of less desirable characteristics.

My invention has for an object the provision of a method and apparatus whereby conversion of a naphtha or gasoline to a product of improved characteristics as to anti-knock value or boiling range or both, and purification of the resultant product from unstable impurities formed as an incident to such conversion may be effected in an advantageous manner.

A further object of my invention is to provide a method and apparatus for cracking and refining heavier oils such as kerosene and gas oil. More particularly, the invention is directed to a continuous process and apparatus wherein gasoline or naphtha is subjected to conversion conditions of temperature and pressure to "re-form" the same and the converted products are, preferably in their entirety, subjected to subsequent treatment with a polymerized catalyst, while at elevated temperature and preferably also under superatmospheric pressure, to effect the conversion of undesirable gum-forming constituents to products of higher boiling point, which can readily be removed from the desired product.

In accordance with my invention, a gasoline, naphtha, kerosene or gas oil which it is desired to improve is passed through a confined zone under high pressures and temperatures for a period of time sufficient to convert the stock into gasoline of increased anti-knock rating or of modified boiling range, or both, and the products leaving the conversion zone are immediately thereafter chilled to a temperature below a conversion temperature, as for example by means of direct contact with hydrocarbon oil, such as refined light stock previously produced by the process or other refined or unrefined oil, either light or heavy. The products are then passed with or without substantial reduction of pressure and with or without further heating through a treating zone where they are subjected to contact with a solid adsorptive catalyst effective to polymerize gum-forming constituents to heavy polymers. The latter are then removed from the light distillate by fractionation, preferably under reduced pressure.

In one form of the invention the entire products from the heat and pressure conversion zone are passed through the treating zone without previous reduction of pressure to any substantial degree, whereby highly efficient operation of the

clay tower is obtained, together with other operative advantages.

The invention will be more fully understood from the following description taken in connection with the accompanying drawings, in which Fig. 1 is a diagrammatic side elevation of an apparatus embodying the principles of the invention when carrying out clay treatment under high pressure and preferably in the liquid phase, and

Fig. 2 is a diagrammatic side elevation of an apparatus embodying the principles of my invention as adapted to vapor-phase clay treatment.

Referring to Fig. 1, the numeral 1 indicates a tank or source of supply of charging stock, for example heavy cracked naphtha, straight run gasoline, kerosene, gas oil or the like. A line 2 having valve 3, booster pump 4, and high pressure pump 5 connected therein leads to a heating coil 6. The heating coil 6 is located in the hot-test portion of a heating chamber 7 forming part of a furnace 8. A line 9 leads to an arrester 10. The arrester 10 is connected to a second arrester 11 by means of pipe 12 controlled by valve 13. A by-pass line 14 controlled by valve 15 connects lines 9 and 12. A withdrawal pipe 16 controlled by valve 17 is connected to the bottom of the arrester 10. A line 18 leads from the bottom of the arrester 11 to the bottom of a clay-treating tower 19, and a pipe 20 having valves 21, 22 and 23 leads from the upper part of the clay tower 19 to the inlet end of a heating coil 24 located in a cooler portion of the furnace 8. A line 25 controlled by a valve 26 connects the outlet end of the heating coil 24 to a fractionating tower 27. A by-pass 28 controlled by valve 29 connects lines 20 and 25. A line 30 having a valve 31 connects the line 25 to a second fractionating tower 32. A line 33 having a valve 34 connects the top of the fractionating tower 27 with the line 30. A draw-off line 35 having a valve 36 leads from the bottom of tower 27. A by-pass 37 controlled by valve 38 connects lines 20 and 30.

From the bottom of the fractionating tower 32 a pipe 40 having valves 41, 42 and 43 and having a pump 44 connected therein leads back to and connects with pipe 2 at a point between the high pressure pump 5 and the heating coil 6. A by-pass 45 controlled by valve 46 is connected in the line 40 around the pump 44. A withdrawal line 47 having a valve 48 is connected to the line 40 between the bottom of the tower 32 and the valve 41. A by-pass 50 connects line 40 with the line 2 before the booster pump 4, and a by-pass 51 connects line 40 with pipe 2 between the booster pump 4 and the high-pressure pump 5. Valves 42 and 43 are located in the line 40 between the by-passes 50 and 51 and between the by-pass 51 and line 2, respectively. A line 55 connects the top of the fractionating tower 32 to a condensing 60

coil 56 which is in turn connected by a line 57 to a high-pressure separator 58. A pipe 59 having a valve 60 is connected to the top of the separator 58 and leads to a gas-recovery plant (not shown). A pipe 61 having a valve 62 connects the upper part of the high-pressure separator 58 to the upper part of a low-pressure separator 63. The separator 63 may be made to serve as a stabilizer by providing a heating coil in the bottom, a cooling coil at the top, and fractionating plates between the coils, (none shown). A pipe 64 leads from the upper part of the low-pressure separator 63. A pipe 65 having a valve 66 leads from the low-pressure separator 63 to a suitable storage tank 67. Connected to the lower portions of the separators 58 and 63 is a pipe 68 having valves 69 and 70. A pipe 71 is connected to the pipe 68 between the valves 69 and 70. A booster pump 72 and a high-pressure pump 73 are connected in the line 71. The pipe 71 has a valve 77 and leads to the upper portion of the arrester 11. A tank 78 is connected by means of a line 79 having a valve 80 to the line 71 at a point between the pipe 68 and the pump 72.

The following is a specific example illustrating my process as it may be carried out in the apparatus shown in Fig. 1, but it will be understood that the specific conditions herein recited 30 may vary in accordance with the nature of the materials treated and the results desired. The process is carried out as follows:

Suitable charging stock, for example a straight-run heavy naphtha having an initial 35 boiling point of from 250° to 350° F. and an end boiling point of from 400° to 500° F. is raised by the booster pump 4 and the high pressure pump 5 to a pressure of from 750 to 2000 pounds per square inch and sent through the heating coil 6 where it is heated to a temperature of from 925° 40 to 1050° F. The products emerging from the coil 6 are then passed through the line 9 into the arrester 11 where they are chilled to a temperature of from 550° to 650° F., preferably from 575° to 600° F., by contact with finished distillate returned from low-pressure and high-pressure 45 separators 63 and 58, or by means of untreated distillate obtained from a cracking operation, stored in tank 78. The distillate used for chilling 50 is raised to a pressure above that maintained in the arrester 11 by means of pumps 72 and 73. The pressure in the arrester 11 is substantially the same as that existing in the coil 6. From the arrester 11, the total products are passed upwardly through a bed of clay or other similar 55 adsorptive catalyst or polymerizing agent contained in the tower 19, preferably without reduction of pressure other than that incident to passage of the products through the catalyst, 60 and wholly or largely in the liquid phase. The products leaving the clay tower 19 are preferably reduced in pressure, for example to a pressure of 40 pounds per square inch, or more, by means of valve 21, valve 38 or valve 22, and then 65 may be passed either through heating coil 24 where the temperature of the oil is raised to approximately 700° F. and then into the fractionating towers 27 or 32, or they may be passed by way of line 37 into tower 32, or by way of line 70 72 into tower 27 without additional heating, depending on whether or not the temperature of the products leaving the tower 19 are at sufficiently high temperature to effect vaporization of the desirable fractions without further addition of heat.

If desired, a portion of the products leaving the clay tower may be passed through the heating coil and the remaining portion may be passed directly into either or both towers 27 and 32. Where the products are first passed through 5 fractionator 27, the light fractions or overhead vapors may be taken off as vapor and further fractionated in tower 32. Recycle stock is removed from the bottom of the tower 32 through the line 40 and the light fractions pass overhead 10 through the line 55 to the condenser 56. The mixture of condensate, gas and uncondensed vapors then passes into the high-pressure separator 58, which may be maintained under a pressure of, for example, approximately 40 15 pounds per square inch, although this pressure is not limited and may be increased or decreased as desired. Gas and uncondensed vapors are withdrawn through the line 59 controlled by valve 60 and may be taken to the gas-recovery 20 plant (not shown) where the condensable portions thereof are recovered. Condensate from the high-pressure separator 58 then passes into the low-pressure separator 63, wherein a low pressure of, for example, atmospheric to 10 25 pounds per square inch gauge, is maintained, and the gases which separate are taken off through the pipe 64 and may be disposed of in any suitable manner as, for example, by being burned as fuel in the furnace. The low-pressure separator 30 may, as aforesaid, contain fractionating plates, a heating coil in the lower part and a cooling coil in the upper part, (none shown) and thereby function as a stabilizer for the liquid before it passes to storage through the line 65. 35

A portion of the condensate in the low- and high-pressure separators may be continuously withdrawn and raised to the pressure existing in the arrester by means of the booster and high-pressure pumps 72 and 73 and sprayed into the 40 top of the arresters through the pipes 74 and 75, respectively.

The pressure in towers 27 and 32 may range from 0 to 150 pounds per square inch, but preferably will be between 40 and 50 pounds per 45 square inch. The temperature of the vapors entering tower 27 may be approximately 700° F., and the temperature of the vapors entering tower 32 may range from 550° to 700° F. A portion of the condensate from tower 32 may be recycled 50 back to heating coil 6. The pressure in the tower 32 and the operation of the pump 44 will determine to what point in the line 2 the recycled stock is returned. If the pressure is near atmospheric, the condensate will be sent through 55 by-pass 50 back to line 2. If the pressure in tower 32 is sufficiently high, the condensate may pass through by-pass 51 to the line 2, or the recycled stock may pass through pump 44 where its pressure is raised sufficiently to inject the 60 condensate into the pipe 2 between the high pressure pump 5 and the heating coil 6. The condensate from tower 32 may or may not be recycled or may be partially recycled. The portion not recycled is withdrawn through the line 65 47. Liquid collected in tower 27 is withdrawn from the system through draw-off pipe 35.

Instead of using the refined distillate from the low- and high-pressure separators as chilling stock, refined or untreated distillate, preferably 70 the gasoline fraction, from a vapor-phase or other cracking operation may be used, or the untreated distillate may supplement the distillates from the low- and high-pressure separators. It will be understood, however, that heavier frac- 75

oils from the oils charged to the coil 121, as in a conventional cracking operation, but to effect a molecular rearrangement, ordinarily known as reforming, of the hydrocarbons of the oil from the paraffinic saturated order into oils containing large percentages of unsaturated aromatic compounds, and to do this with as little formation of fixed gas as is possible. Some adjustment of temperature and pressure conditions within the 5 limits above specified should be effected, depending upon the character of the naphtha used as charging material for the purpose of securing the best results. Such adjustment is, of course, within the skill of the ordinary worker in the art.

10 The reformed unsaturated oils produced by the operation of the still or converter 122 requires some treatment for stabilization purposes before the oils can be used as a completed motor fuel. It has been observed that certain types 15 of unsaturates, especially the diolefines, readily oxidize when exposed to air, and sometimes light, to produce high-boiling compounds known as polymers. These polymers comprise gum-like particles of matter which if permitted to remain 20 in the oil would interfere with its utility as a motor fuel. To effect the removal therefore of these undesirable polymers, the oils or vapors discharged from the coil 121 preferably pass by way of a transfer line 124, lines 125 and 126 into 25 treating chamber or clay tower 127. The line 125 is controlled by valve 128 and the cooler 129 is placed in the line to cool the oil and/or vapors leaving the coil 121 to a temperature suitable for clay treatment. The line 126 is controlled by 30 pressure release valve 130 to lower the pressure on the products passing into the clay tower in order that they may pass through the tower in the vapor state. The products leaving the heating coil 121 instead of passing through line 125 may 35 pass through line 131 controlled by valve 132 in which is placed the shock chiller or arrester 133. Any suitable oil such as disclosed in connection 40 with the arrester in Fig. 1 may be used as chilling medium in the chiller 133. If desired, the products issuing from coil 121 may be passed through lines 125 and 131 simultaneously. In the chamber 45 127 there is arranged an adsorptive catalyst of the nature of fuller's earth, which is designated by the numeral 134. The vapors upon contact with the catalyst are below a cracking temperature and may be under pressure of several hundred pounds. Under these conditions of elevated 50 temperature and pressure, the fuller's earth, bentonite, silica gel, or diatomaceous earth constituting the bed in tower 127, polymerize undesirable 55 unsaturated compounds contained in the vapors into higher boiling compounds known as polymers. These polymers possess a boiling range higher than that of the oils or vapors charged 60 to the chamber 127, indicating the polymerized character thereof.

Following contact with the catalyst 134, the treated oils are passed through line 135 controlled by valve 136 into a separator 137, where the light 65 treated vapors are separated from high-boiling liquid oils. The vapors are drawn off through an overhead line 138 and pass through a cooler or condenser 139, thence through a look-box 140, a gas separator 141, and finally delivered to 70 a storage tank 142 as treated end point motor fuel distillate. The high-boiling liquid oils are removed from the bottom of the separator through a draw-off line 143 controlled by valve 144.

75 It will be understood that a pair or plurality

of the chambers 127 may be provided, whereby when the catalyst in any one of such chambers becomes inactive by reason of adsorbed polymers, that chamber may be cut out of the system and another chamber containing fresh catalyst substituted therefor. A line 145 controlled by valve 146 leading from the converting coil may be provided with an evaporator 147 for the purpose of insuring the delivery of but low-boiling vapors to the catalyst containing chambers, any heavy oil, formed by the conversion reactions in the coil 121 being removed from the bottom of the evaporator through valve controlled draw-off line 148. Also, the bottom of the fractionating tower 106 is provided with a 15 draw-off line 149 for the discharge of liquid high-boiling oil. These oils may be usually employed as charging stocks for associated cracking systems.

It will be seen that I have invented a novel 20 process and apparatus which provides economical operation for producing a finished motor fuel of high anti-detonating value from which the gum-forming constituents have been removed, while avoiding formation of undesirable heavy 25 residues and large gas losses.

This application is a continuation in part of my co-pending application Serial No. 595,585 filed February 27, 1932.

What is claimed is:

1. The method of preparing gasoline of high anti-detonating characteristics and low gum-forming content from naphtha of low anti-detonating characteristics, which comprises heating the naphtha in a restricted stream to a temperature of approximately 1000° F. under a pressure of approximately 1000 pounds per square inch, immediately thereafter suddenly chilling the resulting products to a temperature below conversion temperature and without substantially reducing the pressure thereon, passing the entire resulting products in the absence of added hydrogen through an adsorptive catalyst capable of polymerizing substantially only the objectionable unsaturated constituents into high-boiling hydrocarbons, fractionating the treated products to remove relatively high-boiling products of polymerization formed during contact with said catalyst, and removing the desired treated gasoline.

2. A method according to claim 1 in which the products are chilled by direct contact with light distillate.

3. A method of improving the anti-knock properties and stability of motor fuel which comprises heating a hydrocarbon oil of low anti-knock characteristics consisting principally of constituents within the gasoline and kerosene boiling range to a cracking temperature adequate to improve the anti-knock characteristics thereof, maintaining said oil at said temperature for a period sufficient to effect the desired improvement in the anti-knock characteristics, thereafter suddenly cooling the resulting products to a temperature below the conversion temperature but above the normal vaporizing temperature, thereafter contacting the total resulting products in the absence of added hydrogen with an adsorptive catalyst capable of polymerizing substantially only the objectionable unsaturated constituents into high-boiling hydrocarbons, fractionating the treated products to remove constituents above the gasoline boiling range and separately condensing and collecting 75

tions such as kerosene or even gas oil may be used as chilling stock. Untreated distillate introduced in this manner is of course refined along with the stock from the reforming coil 6.

- 5 When cracking heavier oils such as gas oil and re-cycle stock into lighter fractions, it may in some instances be advantageous to use two arresters. In the first arrester 10 the conversion products are chilled to a temperature of approximately 700° to 800° F. in order to arrest the conversion reaction and to knock out heavy fuel oil which may form as a result of the conversion operation. The fuel oil will be withdrawn from the system through the valve controlled pipe 16.
- 10 15 The uncondensed lighter fractions pass from the arrester 10 into the arrester 11 where the temperature is reduced to from 550° to 650° F. and sent through the clay tower. When operating in this manner the arrester 11 serves as a chiller or cooler to bring the products leaving arrester 10 to a temperature suitable for the clay treatment. From the clay tower the products are preferably passed through the heating coil 24 into the fractionating tower 27 to remove the heavy ends which are withdrawn therefrom through the valve controlled pipe 35. The vapors then pass into the second fractionating tower 32 where they are further separated into finished overhead stock and condensate for 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570
- The clay tower is preferably insulated to maintain the temperature at which the products enter and also in order to avoid to a large extent, subsequent heating for fractionation of the resulting products. Due to the exothermic reaction in the tower, the temperature may rise slightly.
- The following data are the results of actual operations:

	Gas oil	Straight run heavy naphtha	Straight run gasoline
45 Charge per unit day.	3200 bbls.	2500 bbls.	3700 bbls.
Total time through heating coil.	10.8 min.	12 min.	7.4 min.
Time through preheating section of coil.	8.7 min.	8 min.	5.5 min.
Time through conversion section of coil.	2.1 min.	4 min.	1.9 min.
Pump pressure.	1050 lbs.	1200 lbs.	1100 lbs.
Still pressure.	780 lbs.	1000 lbs.	750 lbs.
Pressure at which cooling oil is charged to arrester.	850 lbs.	1050 lbs.	950 lbs.
Clay tower pressure.	700 lbs.	910 lbs.	700 lbs.
50 Fractionating tower pressures.	45 lbs.	46 lbs.	43 lbs.
High pressure gas separator.	39 lbs.	39 lbs.	37 lbs.
Low pressure gas separator.	Atm.	Atm.	Atm.
Furnace temperature.	1200/1500° F.	1200/1500° F.	1200/1500° F.
Still inlet oil temperature.	Atm.	Atm.	Atm.
Still outlet oil temperature.	945° F.	1000° F.	950° F.
Cooling oil charged to arrester.	3350 bbls.	2500 bbls.	3200 bbls.
Temperature of products entering clay tower.	580° F.	580° F.	595° F.
60 Temperature of products leaving clay chamber.	605° F.	590° F.	610° F.
Pressure distillate yield (gasoline).	29.45%	64.18%	90.42%
Gas.	8.38%	13.92%	3.99%
Recycle stock.	59.85%	18.07%	None.
70 Loss.	2.32%	3.63%	5.59%
Time of contact in clay tower.	1.1 min.	1.5 min.	0.9 min.
Octane number before treatment.			48.
Octane number of gasoline after treatment.			63.5.

It will be noted from the above data that the reforming temperature for straight run naphtha is only 950° F. In this instance the main object was to adjust the boiling range of the naphtha without obtaining a large increase in anti-detonating characteristics.

It will also be noted that the pressures in the clay towers are somewhat lower than the still pressures. This drop is due to the line drop together with the cooling of the oil effected in the 10 arrester.

Although temperatures of 925° to 1050° F. have been indicated for the conversion step, it will be understood that temperatures as low as 850° F. and as high as 1300° F. may be used, depending 15 on the oil to be treated and the results desired. The pressure should be at least sufficient to maintain the oil substantially in the liquid phase during the clay treatment.

Referring to Fig. 2, the numeral 101 designates 20 a tank or other container adapted for the reception of crude oil from which leads a pipe line 102. Arranged in the pipe line is a pump 103 for advancing the oil under pressure through the heating coil 104 of a skimming or topping still 25 105. During the passage of the oil through the coil 104, the said oil is heated sufficiently to vaporize its lower boiling compounds up to and including the naphthas or kerosene contents thereof. The heated oils discharged from the 30 coil 104 pass into a fractionating tower 106, which is operated at temperatures permitting of the withdrawal as vapors of light naphtha from the top of the tower. The vaporized light naphtha travels through an overhead pipe line 107 and 35 is condensed in the cooler 108 and delivered to a separator 109. A gas line leads from the top of the separator and the light naphtha is drawn off from the bottom of said separator through a float valve control line 111 passing through a 40 look-box 112 and thence to a storage container 113.

From the side of the tower 106, at a position midway of its height, there is provided a lateral draw-off line 114 through which a condensate in 45 the form of heavy naphtha is removed from the tower. Thus condensate is passed through a cooler 115, thence through a look-box 116 to a container 117. It is to the treatment of this heavy naphtha as received within the container 50 117, that the present invention is particularly directed.

Leading from the container 117 is a transfer line 118 which is provided with a valve 119 and a pump 120 which is employed to force the heavy naphtha, withdrawn from the tank 117, through the heating coil 121 of a conversion furnace 122. The furnace 122 may be of any standard construction including outer heat retaining walls and provided with one or more burners 123 for the development of heated gases of combustion which are used in raising the temperature of the oil passing through the coil 121 through reforming or converting temperatures. Usually, these temperatures vary between 1000 to 1350° F., or in other words, typical vapor phase converting temperatures. The pressures in the coil 121 may vary from slightly above atmospheric to pressures of the order of several hundred pounds per square inch, and preferred pressure range varies between 300 to 800 pounds per square inch. The vaporized oils passing through the coil 121 are therefore subjected to conversion conditions, that is to say, no effort is made to effect the formation of considerable quantities of lower-boiling 75

gasoline constituents as a final product of the process.

4. A method of improving the anti-knock properties and stability of motor fuel which comprises heating a light hydrocarbon oil having low anti-knock properties consisting principally of constituents within the gasoline boiling range to a cracking temperature adequate to improve the anti-knock characteristics of said oil, maintaining said oil at said cracking temperature for a period sufficient to improve the anti-knock properties thereof to the desired extent, thereafter suddenly cooling the resulting products below active cracking temperature but above the normal vaporizing temperature of the original oil, contacting the total products in the absence of added hydrogen while at said reduced temperature with a solid adsorptive catalyst capable of polymerizing substantially only the objectionable unsaturates for a period adequate to form a stable gasoline product, thereafter fractionating the treated products into a high-boiling fraction above the gasoline boiling range and a fraction within the gasoline boiling range and removing said last-named fraction as a final product of the process.

5. A method of improving the anti-knock properties and stability of motor fuel which comprises heating a heavy naphtha fraction consisting principally of higher-boiling constituents of gasoline having relatively low anti-knock properties to a temperature between 925° F. and 1050° F. while under a pressure between 750 and 2000 pounds per square inch, maintaining said heavy naphtha at said elevated temperature and pressure for a period adequate to improve the anti-knock properties thereof the desired amount, thereafter suddenly cooling the resulting products to below cracking temperature but above the normal vaporizing temperature of said heavy naphtha, contacting the total resulting products in the absence of added hydrogen while at said reduced temperature with a solid adsorptive catalyst capable of polymerizing substantially only the objectionable color-imparting and gum-forming constituents thereof and thereafter separating a fraction within the gasoline boiling range from the products so treated as a final product of the process.

6. A method of improving the anti-knock properties and stability of motor fuel which comprises heating a light hydrocarbon oil having low anti-knock properties and consisting principally of constituents boiling within the gasoline and kerosene boiling range to a cracking temperature adequate to reform the gasoline constituents to improve the anti-knock properties thereof, maintaining said oil at said cracking temperature for a period adequate to improve the anti-knock properties to the desired extent, thereafter commingling the resulting products with a relatively cooler stream of light hydrocarbon oil consisting principally of constituents within the gasoline and kerosene boiling range to suddenly reduce the temperature of the heated products to below cracking temperature but above the normal vaporizing temperature thereof, thereafter contacting the total mixture in the absence of added hydrogen with a solid adsorptive catalyst capable of polymerizing substantially only the objectionable color-imparting and gum-forming constituents thereof, fractionating the products resulting from said last-named treatment to separate a fraction within the gasoline boiling range as a final product of the process.

7. A method of improving the anti-knock properties and stability of motor fuel which comprises heating a light hydrocarbon oil consisting principally of gasoline and kerosene constituents to a cracking temperature adequate to reform the gasoline constituents into products of improved anti-knock properties, maintaining said oil at said cracking temperature under a superatmospheric pressure, subjecting said oil to said high temperature treatment for a period adequate to improve the anti-knock properties thereof the desired extent, thereafter admixing the resulting heated products with a low temperature, light hydrocarbon oil having low anti-knock characteristics and consisting principally of constituents within the gasoline and kerosene boiling range to suddenly reduce the temperature of the heated products to below cracking temperature but above the normal vaporizing temperature thereof, thereafter contacting the total resulting mixture in the absence of added hydrogen with a solid adsorptive catalyst capable of polymerizing substantially only the objectionable color-imparting and gum-forming constituents and fractionating the products resulting from said last-named treatment to separate a distillate within the gasoline boiling range.

8. A method of improving the anti-knock properties and stability of motor fuel which comprises heating a light hydrocarbon oil consisting principally of gasoline constituents to a cracking temperature adequate to reform the gasoline constituents into compounds having improved anti-knock properties, maintaining said oil at said cracking temperature for a period adequate to improve the anti-knock properties thereof the desired extent, thereafter admixing said oil with a relatively cooler light hydrocarbon oil having low anti-knock properties to suddenly reduce the temperature of the heated products to below cracking temperature but above the normal vaporizing temperature thereof, thereafter contacting the total mixture in the absence of added hydrogen with a solid adsorptive catalyst capable of polymerizing substantially only the objectionable color-imparting and gum-forming constituents, maintaining said mixture while in contact with said solid adsorptive catalyst under a pressure adequate to maintain a substantial portion of said mixture in liquid phase and fractionating the products resulting from the last-named treatment to separate a motor fuel within the gasoline boiling range.

9. The method of improving the anti-knock properties and stability of motor fuel which comprises heating a light hydrocarbon oil having low anti-knock properties consisting principally of constituents within the gasoline boiling range to a cracking temperature adequate to improve the anti-knock characteristics of said oil while being maintained under superatmospheric pressure, maintaining said oil at said cracking temperature and under said superatmospheric pressure for a period sufficient to improve the anti-knock properties thereof, suddenly cooling the resulting products at substantially said pressure to a temperature below cracking, contacting the total resulting products while at said reduced temperature, without reduction of pressure and in the absence of added hydrogen, with a solid adsorptive catalyst capable of polymerizing substantially only the objectionable unsaturates, thereafter fractionating the treated products into a high-boiling fraction above the gasoline boiling

range and a fraction within the gasoline range, and recovering said last-mentioned fraction.

10. The method in accordance with claim 6 wherein the light hydrocarbon oil used to suddenly reduce the temperature of the heated products is an untreated light oil containing color-imparting and gum-forming constituents.

11. The method in accordance with claim 7 wherein the light hydrocarbon oil used to suddenly reduce the temperature of the heated products is an untreated light oil containing color-imparting and gum-forming constituents.

RUDOLPH C. OSTERSTROM.
